(57) **CLAIM**

The ornamental design for a modular charger for a gaming console, as shown and described.

DESCRIPTION

FIG. 1 is a front-right perspective view of a modular charger for a gaming console showing my new design;

FIG. 2 is a front-left perspective view of the modular charger for a gaming console of FIG. 1;

FIG. 3 is a rear-right perspective view of the modular charger for a gaming console of FIG. 1;

FIG. 4 is a top view of the modular charger for a gaming console of FIG. 1;

FIG. 5 is a bottom view of the modular charger for a gaming console of FIG. 1;

FIG. 6 is a right side view of the modular charger for a gaming console of FIG. 1, the left-side view being the mirror image of FIG. 6;

FIG. 7 is a front view of the modular charger for a gaming console of FIG. 1; and,

FIG. 8 is a rear view of the modular charger for a gaming console of FIG. 1.

The broken lines are for environmental purposes only and form no part of the claimed design.
